J. M. BARDERA

SUGAR HOLDER

Filed June 18, 1920

Fig. 1.

Inventor
JOSE MARTINEZ BARDERA
By his Attorney
Morris Finsterstein

UNITED STATES PATENT OFFICE.

JOSE MARTINEZ BARDERA, OF NEW YORK, N. Y.

SUGAR HOLDER.

Application filed June 18, 1920. Serial No. 389,936.

To all whom it may concern:

Be it known that JOSE MARTINEZ BARDERA, a subject of the King of Spain, and resident of the city of New York, in the county of Kings and State of New York, has invented certain new and useful Improvements in Sugar Holders, of which the following is a specification.

This invention relates to sugar containers. 10 One object thereof is to provide a device of this type which shall be both sanitary and economical in use.

Another object of this invention is to provide a sugar dispenser having the above 15 characteristics which shall be simple and neat in construction, cheap to manufacture and easy to manipulate.

Other objects of this invention will be in part obvious and in part hereinafter pointed 20 out.

The invention accordingly consists in the features of construction, combinations of elements and arrangement of parts which will be exemplified in the construction hereinafter described and of which the scope of 25 application will be indicated in the following claim.

In the accompanying drawings, in which is shown one of various possible illustrative 30 embodiments of this invention.

Fig. 1 is a vertical elevation in section of a sugar dispenser embodying the invention; and

Fig. 2 is a plan view thereof.

Referring in detail to the drawing, 35 indicates a sugar container made of any suitable material such as glass for example, and being threaded adjacent the top as at 40 11 for the removable cover 12. This cover is made preferably of metal and comprises a 45 curved top portion 13 formed at one end with a nozzle or spout 14 bent from the material of the cover as will appear from the drawing, and through which the contents of the container are dispensed. The 50 interior of the container is protected against germs and dust and other such contamination by a sanitary cover member 15 which is hinged as at 16 to the nozzle and is preferably in the form of a cap having an annu-

lar portion 17 adapted to fit snugly around the neck of the nozzle. This cover 15 is further adapted to swing back on its hinge by its own weight when the container is tilted so as to dispense the sugar as shown 55 in dotted lines in Fig. 1. In this manner, the sugar is dispensed from the container without the necessity of introducing any spoons or the fingers thereinto. The dispensing takes place automatically on handling only of the outside of the container body and tilting the same. An added advantage is that only a small amount of the sugar can be dispensed at a time in this way, and the person handling the container can easily 60 adjust the supply to his needs, thus making for high economy.

It will thus be seen that there is provided apparatus in which the several objects of this invention are achieved and which is 70 well adapted to meet the conditions of practical use.

As various possible embodiments might be made of the above invention and as various changes might be made in the embodiment 75 above set forth, it is to be understood that all matter herein set forth or shown in the accompanying drawings is to be interpreted as illustrative and not in a limiting sense.

Having thus described my invention, I 80 claim as new and desire to secure by Letters Patent:—

A sugar dispenser comprising a cylindrical receptacle of material having threads on the exterior surface thereof adjacent its 85 free opening, a cover securely mounted thereon to normally form a complete closure for said receptacle, said cover comprising a unitary curved top portion with a spout formed near its outer edge integral therewith and angularly projecting outwardly and upwardly thereof beyond the side of the receptacle, a cylindrical ring member integral with said top portion having the interior surface thereof threaded to fit the 90 threaded end of the receptacle, the juncture of the outer edge of said spout with said cylindrical ring member being in line with the outer surface of the cylindrical receptacle, and a cap hinged to an edge of the spout 100

opening normally in position to close the latter, said spout having an outlet in a plane normally at an angle with the horizontal, said cap arranged to swing open when the ⁵ dispenser is tilted less than 90° from its normal vertical upright position, and to simultaneously swing back to its effective

closure position when the dispenser thereafter is returned to its initial position.

Signed at New York city, in the county of ^{1c} New York, and State of New York, this 11th day of June, A. D. 1920.

JOSE MARTINEZ BARDERA.
